CLAIM

The ornamental design for a transaction card as shown and described.

DESCRIPTION

FIG. 1 is a top, front, right perspective view of the claimed design for a transaction card;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right perspective view of the claimed design for a transaction card shown in an alternative unclaimed environment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

In the drawing, the sets of parallel lines indicate surface shading. The broken lines immediately adjacent to the shaded area depict boundaries of the claimed design and form no part thereof. The broken lines showing the remainder of the transaction card depict environmental structure and form no part of the claimed design. The unshaded regions within the claimed region that broken lines demarcate form no part of the claimed design.
